(57) **CLAIM**

The ornamental design for a bedsheets with mesh inserts, as shown and described.

DESCRIPTION

FIG. 1 is a top view of the bedsheets with mesh inserts showing the new design.

FIG. 2 is a bottom view of the bedsheets with mesh inserts shown in FIG. 1.

FIG. 3 is a top, detail view of the mesh insert portion of the bedsheets with mesh inserts shown in FIG. 1.

FIG. 4 is a bottom, detail view of the mesh insert portion of the bedsheets with mesh inserts shown in FIG. 1.

FIG. 5 is a front, perspective view of the bedsheets with mesh inserts shown in FIG. 1, where the bedsheets is depicted as covering the top of a mattress.

FIG. 6 is a top view of the bedsheets with mesh inserts shown in FIG. 1, where the bedsheets is depicted as covering the top of a mattress.

FIG. 7 is a left, side view of the bedsheets with mesh inserts shown in FIG. 1, where the bedsheets is depicted as covering the top of a mattress; and,

FIG. 8 is a right, side view of the bedsheets with mesh inserts shown in FIG. 1, where the bedsheets is depicted as covering the top of a mattress.

Broken lines shown in the drawings are for the purpose of illustrating environmental structure or to define boundaries and form no part of the claimed design.

1 Claim, 7 Drawing Sheets
